UNITED STATES PATENT OFFICE.

ANDREW J. BROOKINS, OF CHICAGO, ILLINOIS.

RAMP-RAIL INSTALLATION.

1,392,111.

Specification of Letters Patent. Patented Sept. 27, 1921.

Application filed October 18, 1920. Serial No. 417,705.

To all whom it may concern:

Be it known that I, ANDREW J. BROOKINS, a citizen of the United States, and a resident of Chicago, in the county of Cook and State 5 of Illinois, have invented certain new and useful Improvements in Ramp-Rail Installation, of which the following, reference being had to the drawing accompanying and forming a part thereof, is a specification.

- 10 This invention relates to the ramp rail of a block signal railway system, wherein a ramp rail, (or ramp), track and track side electric circuits, with energizing means, are used as elements of the installation.
- 15 Among the objects of this invention are, to obtain an installation of a ramp which will, automatically, indicate "danger" to control circuits of predetermined blocks in case that any essential elements of the ramp 20 are removed or misplaced; and an installation which automatically indicates the breaking down of the insulation separating the several sections of the ramp.

In a block signal system of which this invention is adapted to be applied the track of a given block is an element of a circuit which comprises the rails of said track, the coils of an electro-responsive device arranged to control movable conductors which form 30 elements of a track side circuit, or circuits, electric conductors which connect the said rails and coils of said electro-responsive device, and means to energize the track circuit formed thereby; the arrangement of said 35 track circuit being such that proper energizing of said coils moves into, and maintains said movable conductors of the track side circuit in electrical contact with corresponding contact points, and when a motor, engine 40 or car, moves on to the given block, said coils are shunted and become insufficiently energized to maintain said contact; said arrangement also being such that when a rail or the track of said block is removed, or 45 broken, said track circuit is broken, and said coil becomes "dead."

In reducing this invention to practice I obtain the same control of said track circuit in case of the misplacement of the ramp, or 50 of any section thereof, that is obtained, as last above described, when a rail of said track is removed or broken.

This invention is also adapted to be applied to block signal systems working in 55 conjunction with automatic train carried apparatus, wherein cab carried apparatus is

controlled by a ramp and its energized or non-energized electrical conditions, said ramp being an element of the track side circuit hereinbefore mentioned; it being well known that in said cab installations cab carried conductors and electroresponsive apparatus form, at intervals, elements of a circuit, or circuits, of which said ramp and track side installations also are elements; 60 and in reducing this invention to practice I obtain a similar control of said cab carried installations, on the breaking down of the insulation of said ramp section that is obtained in the case of the shunting of the 65 coils of an electroresponsive apparatus of the track circuit when a motor, engine or car is on the rails of a block.

In the drawing referred to Figure 1 is a side elevation of a track of a railway, a ramp 70 embodying this invention, a truck and a cab carried apparatus thereon, arranged to coact with said ramp.

Fig. 2 is a plan view of a railway track, an installation embodying this invention, 75 and a diagram of track and track side circuits co-acting therewith.

Fig. 3 is a section of a rail of a track, and an illustration partly in vertical section and partly in elevation, of members forming ele- 80

ments of the invention.

Fig. 4 is a horizontal section on line 4-4 of Fig. 3, viewed as indicated by arrows.

A reference character applied to designate a given part indicates said part throughout 90 the several figures of the drawing wherever the same appears.

1, 2, 3, respectively represent what is termed a block of a railway signal installation, and 4 a portion of an additional block. 95 A, B, represent insulation between adjacent ends of rails $a^1 a^2, a^2 a^3, a^3 a^4$, and $b^1 b^2, b^2 b^3, b^3 b^4$. C, C, represent tie plates joining the adjacent ends of rails $a^1 a^2, a^2 a^3, a^3 a^4, b^1 b^2, b^2 b^3, b^3 b^4$, respectively, and said tie plates 100 are separated from the rails by insulation, in the usual manner. D represents a ramp, which is illustrated as consisting of ascending section d and descending section d^1 . E¹, E², E³, represent plates which form the 105 ramp ends of bars I¹, I², I³, (hereinafter described), and e¹, e², e³ represent tie plates corresponding with plates E¹, E², E³.

Plates E¹, E², E³, and e¹, e², e³, are of electric conducting material, and are positioned on opposite sides of sections d , d^1 , of ramp D, but insulated therefrom, as herein-

after described. F, G, represent members of electric conducting and preferably resilient material, which electrically connect the plate E on one side of the sections of the ramp 5 with the plate e on the other side of said sections. These members F, G, are held in electrical contact with each other and with said plates E, e, by the ramp sections and connecting members, when said sections are 10 properly in place and insulated. When a section of the ramp is removed, or said connecting members are misplaced, one of said members, F, G, springs or drops from contact with the other, thereby opening the circuit 15 cuit hereinafter termed the detector circuit, of which said plates, hereinafter termed detector plates, are elements. Said detector plates are separated from the sections d, d', of ramp D, by insulations H, h, respectively.

20 Referring to Fig. 3, plate E is illustrated as integral with bar I, as before stated, and in electrical connection with rail a¹ by means of said bar; and a plurality of bars I, are illustrated in Fig. 2 as electrically connecting plates E of ramps to a rail of the 25 track.

J, J, represent bolts; K, K, represent insulation tubes on said bolts; k, k, washers of insulating material, and l, l, washers of 30 conducting material. Bar I is illustrated as secured to a rail (a), by the curved end i, bolt i⁴, member i⁵ and bolt i⁶. i⁷, (Fig. 3), represents an abutment on bar I, integral therewith and at right angles to the body 35 thereof, through which the bolt i⁶ extends and by means whereof the member i⁵ is forced into close contact with the base of the rail (a, Fig. 3), by the tightening of nut i⁸ on said bolt.

40 The bar I is illustrated, (Fig. 3), as a right angle bar, and the apex of the ramp sections is secured thereto, by the members hereinbefore described.

Bolts J, J, extend through apertures 45 provided therefor in sections d, d', insulations H, H, and h, h, and k, k, said apertures being so related that the detector plates are forced into electrical contact with each other, to form a continuous conductor between 50 plates E, e, when said members are all in proper relation and the nuts on said bolts are tightened, as illustrated.

Each block of the railway is provided 55 with a battery or electric generator having similar connections. M¹ represents said battery in block 1, M² in block 2, and M³ in block 3.

In Fig. 2 the connections of the batteries M¹, M², M³, are illustrated, and comprise 60 conductors m¹, m², m³, to rails a¹, a², a³; conductors n¹, n², n³, from the batteries to movable conductors N¹, N², N³; contact points O¹, O², O³, and conductors P¹, P², P³, to rails b¹, b², b³. Each block of the railway is provided 65 with the above described installation.

Each block is also provided with the additional installations which are illustrated in Fig. 2 as installed in blocks 1, 2 and 3, comprising a battery (Q¹, Q², Q³) an electromagnet, (R¹, R², R³) a conductor (S¹, S², 70 S³), from battery, (Q¹, Q², Q³), to electromagnet (R¹, R², R³), and a conductor (T¹, T², T³), from said magnet to the curved end (i¹, i², i³) of the connecting bar (I¹, I², I³) in said block, plate (E¹, E², E³) integral 75 with said bars; detector plates (G¹, G², G³, and F¹, F², F³), to tie plate (e¹, e², e³), on the opposite side of the ramp sections. Plates e¹, e², e³, are respectively held rigidly 80 against insulation H, H, h, h, by bolts J, J, said bolts and insulation also holding the detector plates G, F, in close contact with tie plates E¹ e¹; E² e²; E³ e³, and with each other.

Said installation also comprises, from 85 said tie plates e¹, e², e³, conductors y¹, t¹; y², t²; y³, t³, to batteries Q¹, Q², Q³, respectively. It will be observed that the several tie plates (E, e) and detector plates (G, F), of the ramp (D), by the last described connections are arranged in series on the track 90 side circuit which is thereby formed, and energized by the battery of said circuit; that said track side circuit is a local circuit which controls the circuit hereinbefore described, which includes batteries M¹, M², M³, of blocks 1, 2, 3, conductors n¹, n², n³, movable conductors N¹, N², N³, contact points O¹, O², O³, conductors P¹, P², P³, and rails b¹, b², b³, conductors U², U³, U⁴, (at the left 95 hand end of the respective sections or blocks, Fig. 2), relays V², V³, V⁴, and conductors u², u³, u⁴ to rails a², a³, a⁴. The position of the conductor U, relay V and conductor u in block 1 being at the extreme left hand of 100 said block as viewed in Fig. 2, said members are not illustrated, but are similar in position and construction as the same elements in blocks 2, 3 and 4, which are illustrated.

The circuit which comprises, (among 110 other elements) battery Q and electromagnet R, controls the circuit of the block, in addition to the control ordinarily provided for said circuit, (in each block), (said ordinary control forming no part of this invention). A sufficient number of the elements of said ordinary block circuits are illustrated and are about to be described to enable those skilled in the art to understand the relation of the embodiment of 115 this invention thereto. The track side circuit comprises, in addition to battery M, and the elements recited as in said circuit, the ordinary controlled circuit comprising batteries W¹, W², W³, conductors X¹, X², 120 X³, Y¹, Y², Y³, y³, movable conductors Z¹, Z², Z³, and contact points z¹, z², z³. Conductors X¹, X², X³, connect batteries W¹, W², W³, and movable conductors Z¹, Z², Z³; 125 conductors Y¹, Y², Y³ connect contact points 130

z^1, z^2, z^3 with descending section d^1 of ramps D^1, D^2, D^3 ; and conductors y^1, y^2, y^3 , connect tie plates e^1, e^2, e^3 , to the other pole of said batteries W^1, W^2, W^3 ; and the circuit comprising said elements is the ordinary ramp rail partial circuit of said several blocks, which are completed at intervals when the shoe of the cab carried apparatus coming in contact with the descending section of the ramp.

From the foregoing description of the several installations which are illustrated, (said installations comprising existing circuits and additions to existing circuits), it is evident that the circuits of which the batteries Q^1, Q^2, Q^3 , conductors S^1, S^2, S^3 , coils of electromagnets R^1, R^2, R^3 , conductors T^1, T^2, T^3 , connecting bars I^1, I^2, I^3 , detector plates G^1, G^2, G^3 and F^1, F^2, F^3 , tie plates $E^1, e^1, E^2, e^2, E^3, e^3$ and conductors t^1, t^2, t^3 are elements, are normally closed and energized circuits, and that the continuity of the several additional circuits which are some fully and some partially, illustrated, depend on said normal condition of the above described circuits being maintained; it therefore occurs that on the misplacement of any section of ramps D^1, D^2, D^3 , the continuity of the circuits comprising batteries Q^1, Q^2, Q^3 , and the coils of electromagnets R^1, R^2, R^3 , become broken; said magnet becomes deenergized; and the movable conductors N^1, N^2, N^3 , separate from electrical contact with contact points O^1, O^2, O^3 ; and that thereby the continuity of the circuits of which said movable conductors are elements is broken, said circuit, in a given block, comprising battery M , conductor n , movable conductor N , contact point O , conductor P , track rail b , conductor U , coils of electromagnet V (relay V), conductor u , track rail a and conductor m .

The partial track side circuits known in the art and which in this installation comprises as elements thereof the additional detector plates F, G , and consists in a given block, of battery W , conductor y , tie plate e , said plates F, G , plate E on bar I and said bar, rail a , and from the other pole of said battery W , conductor X , movable conductor Z , contact point z , conductor Y , and the descending section d^1 of ramp D . Said descending section d^1 , of ramp D , co-acts, when in normal condition, with cab carried apparatus, and said circuits are successively completed thereby; and on the breaking down of the insulation between sections d, d^1 , said partial circuits are not in normal condition; but a continuous track side circuit is formed, comprising battery W , conductor X , movable conductor Z , contact point z , conductor Y , descending section d^1 of ramp D , detector plates F, G , tie member e , and conductors y and t to said battery, in a given block. This track side circuit is

branched from said point of defective insulation to the descending section of the ramp; one branch including the electrical elements of the cab carried apparatus, which is shunted by the continuous track side circuit last above set forth; said last circuit is of lower resistance than the one including said cab carried elements; hence, said cab carried electrical apparatus, depending for its operation on current from the ramp sections, as they are successively engaged by the shoe of the cab carried apparatus, will be shunted when said shoe comes in contact with a ramp, causing a "stop" or "danger" operation of said cab carried apparatus.

It will be observed that upon the deenergizing of a relay R , in a given block, as say, relay R^2 in block 2, and the consequent breaking of electrical contact between movable conductor N^2 and contact point O^2 , the circuit of which said movable conductor and contact point are elements, will be broken and deenergized, and relay V^2 will become deenergized, and movable conductor Z^1 will break contact with contact point z^1 , and thereby the circuit in block 1, of which said movable conductor and contact point are elements, will be broken, and the descending section d^1 of ramp D^1 will be deenergized; that is, on the misplacement of a ramp in a given block a danger signal is given on the contact of the shoe of cab carried apparatus with the ramp in a preceding block.

I claim:

1. In a track way divided into electrically insulated blocks, and provided at stated intervals with electric circuits comprising cab carried members and track side members, means to shunt said cab carried members at said stated intervals, said means to shunt comprising normally insulated electric conducting members adapted, upon the breaking down of said insulation, to form elements of an auxiliary circuit parallel to and of less electrical resistance than said cab carried elements.

2. A track way divided into electrically insulated blocks, a sectional member in each of said blocks, tie members adapted to hold said sectional members in a determined position, electric conducting members in electric communication with each other and with said tie members, means to insulate said sectional members from said tie members and from said electric conducting members, in combination with road side elements arranged to co-act with cab carried elements comprising an electroresponsive device to form an electric circuit, all arranged so that on the breaking down of said means to insulate, said tie members and said electric conducting members are elements of an auxiliary circuit parallel to said cab carried elements thereof, and of less electrical re-

100

105

110

115

120

130

- sistance, to shunt said cab carried elements.
3. A track way divided into blocks, a sectional member in each of said blocks, tie members to said sections, an electric conducting member secured to the track way and to said tie members and arranged to maintain said track way and said sectional members in spaced relation, means, comprising an electric circuit controlled by the condition of said blocks, in combination with additional electric conducting members insulated from said sectional members and in electric communication with each other and with said tie members, when in normal position, an additional electric circuit comprising said additional electric conducting members, additional electric conductors, said tie members, a source of electrical energy, and an electroresponsive device, all arranged so that the maintaining of said normal position of said additional electric conducting members controls the continuity of said first electric circuit.
4. In a ramp rail installation, comprising a road side member in spaced relation to rails of a track way, tie members to said road side member, said road side member positioned between said tie members and insulated therefrom, and an electric conducting member arranged to maintain said spaced relation, in combination with means to hold said electric conducting member in electrical contact with said tie members, all arranged to form a road side electric circuit comprising as elements thereof a source of electrical energy, an electroresponsive device, said tie members and said electrical conducting member.
5. In a railway block system consisting of a track way divided into electrically insulated blocks respectively provided with a track circuit and with a sectional road side member, tie members arranged, said tie members and said sectional road side member in normal condition, to join the sections, insulation interposed between said road side member and said tie members, means consisting of an electric conductor in electric communication with said tie members, to maintain said road side member in spaced relation to said track way, in combination with means to automatically break the continuity of said track circuit upon the breaking of said normal condition, said means to break comprising electric conductors in electric contact with each other and with said tie members arranged to be maintained in said contact by said normal condition.
6. A ramp comprising a plurality of insulated sections, in combination with a source of electrical energy, electrically connected tie members to said sections, means to insulate said tie members from said sections, and conductors, one whereof electrically connects said source to a predetermined one of said sections and the other electrically connects said source to said tie members, whereby, on the breaking down of said insulation said recited tie members form elements of a continuous and energized electric circuit.
7. A ramp rail comprising a plurality of sections, tie members to join said sections and insulated therefrom, an electric conducting member to electrically connect said tie members to a rail of a trackway, means to selectively energize a predetermined one of said sections, said means having as elements thereof a source of electrical energy, a conductor from said source to said predetermined section and an additional conductor from said source to said tie members; and said means adapted to form a closed and energized electric circuit upon the breaking down of said insulating means.
8. In a block signal railway system having a trackway divided into blocks respectively provided with a source of electrical energy, with conductors and with a roadside member in spaced relation with adjacent rails of said trackway, an additional circuit comprising, in combination, an additional source of electrical energy, electrically connected tie members to said roadside member, said tie members arranged in series and insulated from said roadside member, an electric conducting member arranged to maintain said spaced relation of said roadside member to said trackway and in electric connection with said tie members, an electroresponsive member provided with a coil, and additional conductors electrically connecting said additional source of electrical energy to said tie members and to said coil and from said coil to said electric conducting member, and means controlled by said electro-responsive member to control the continuity of said roadside conductors in adjacent blocks.
9. In a ramp rail installation, a sectional member in spaced relation to a rail of a track, electrically connected tie members to hold the sections of said member in a predetermined position, insulation between said sections and said tie members, a conductor from one of said tie members to said rail, an electroresponsive member, a conductor from the other of said tie members to the coil of said electroresponsive member, and from said coil to said rail, a battery, said rail, said first conductor, said battery and said coil, forming elements of a roadside electric circuit, and said electroresponsive member acting as a control of a roadside circuit of an adjacent block in which a similarly installed sectional roadside member is an element.
10. In a train control system having a trackway consisting of a plurality of insulated blocks, a plurality of track side cir-

cuits respectively provided with an electro-responsive member and means to control said member, said means to control comprising in combination road side elements 5 in spaced relation to the rails of the track way, electrically connected tie members in each of said blocks to join corresponding ones of said road side elements, means to insulate said tie members, an electric conducting member to electrically connect one 10 of said tie members to a rail of said track-

way, a source of electrical energy, an additional electroresponsive member provided with a coil, conductors electrically connecting said coil to said rail and to source of 15 electrical energy and a conductor electrically connecting said source of electrical energy to the other one of said tie members.
